UNITED STATES PATENT OFFICE.

CLIFFORD C. CHICKERING, OF CHICAGO, ILLINOIS.

PIANO.

1,034,082.

Specification of Letters Patent. Patented July 30, 1912.

Application filed November 23, 1908. Serial No. 463,939.

To all whom it may concern:

Be it known that I, CLIFFORD C. CHICKERING, a citizen of the United States, and a resident of the city of Chicago, in the county 5 of Cook and State of Illinois, have invented certain new and useful Improvements in Pianos; and I do hereby declare that the following is a full, clear, and exact description of the same, reference being had to the 10 accompanying drawings, and to the letters of reference marked thereon, which form a part of this specification.

My invention relates to upright pianos, and is designed to provide certain improvements in the construction and in the mounting of the sounding boards and string plates thereof, as will be hereinafter more definitely pointed out and claimed reference being had to the accompanying drawings, in 15 which:—

Figure 1 is a face view of my improved string plate shown rigidly attached to the sounding board. Fig. 2 is a rear elevation of the piano back showing the vertical posts 20 of the frame in dotted lines, and showing the sounding board and its rim rigidly attached thereto. Fig. 3 is a fragmentary section taken on the line 3—3, Fig. 1. Fig. 4 is a similar view taken on the line 4—4, Fig. 1.

In the said drawings: A, indicates the sounding board having the usual wooden diagonal ribs *a*, rigidly secured on the back by gluing, screwing, or otherwise, said sounding board being fitted in the piano 30 frame or case as is usual. Rigidly secured on the back of the sounding board is a rim B. This, as shown, is made up of thin strips of wood glued together and affords a continuous band extending from the upper 35 treble corner of the sounding board laterally and curving downwardly along the opposite side of the piano and curving inwardly along the bottom of the piano frame, thence obliquely upward in a compound curve, and 40 to near the starting point and adjacent the end of the piano and thence up to the starting point where the ends of said rim are 45

rigidly secured together in any suitable manner. The general form of that portion of the sounding board defined by the rim is 50 that of the sounding board of a grand piano and as shown, said rim is beveled under on the inner side adjacent the sounding board and engages over the beveled ends *a'*, of said diagonal ribs *a*. On the opposite side 55 of the sounding board is the string plate C, which is secured in place by means of screws *c*, which extend through posts *c'*—*c*², and are threaded into the outer frame posts D of the piano. As shown, the posts *c'*, fit 60 loosely to the screws and project outwardly to space the string plate the desired distance from the sounding board,

The iron string plate is constructed as is usual with the string plate for grand pianos 65 so far as is practicable in this adaptation—in fact, in all particulars, so far as possible, conditions in a grand piano are duplicated.

Of course, details of the construction may be varied, I therefore do not purpose limiting myself otherwise than necessitated by 70 the prior art.

I claim as my invention:

1. An upright piano, comprising a sounding board, ribs secured thereto, and a rim 75 comprising a laminated band disposed on one face of said sounding board and having all of its corners rounded except where its ends are brought together, said rim having an under beveled face, and said ribs having 80 beveled ends engaging said beveled face of said rim.

2. An upright piano, comprising a sounding board, a rim on said sounding board having a beveled face, and ribs having beveled ends engaging beneath the beveled face of said rim. 85

In testimony whereof I have hereunto subscribed my name in the presence of two subscribing witnesses.

CLIFFORD C. CHICKERING.

Witnesses:

WALTER E. FOX,
K. E. HANNAH.
